CONTAINER CLOSURE

Vernon D. Howe, Sr., Buffalo, N. Y.

Application January 11, 1950; Serial No. 137,930

3 Claims. (Cl. 220—24)

1

My invention relates in general to coin banks, and in particular to the closure plates for the access openings of such banks.

It is well known to those skilled in the art that heretofore coin banks of a certain type were made of cast iron and provided in the bottom with an access opening through which money deposited within the bank might be readily removed. Such openings are closed by a single-piece door or plate usually held in place by means of an inexpensive lock. In some cases, such closure plate is circular and is formed with cam faces which engage the rim surrounding the access opening.

The principal object of my invention is to provide means for closing the opening in the bottom of such banks and which may be fastened in place or removable by means of a screw driver.

Another object is to provide a two-part closure plate having the parts held together by means of a single screw which need only be loosened when the plate is to be removed from the bank.

A further object is to provide a closure plate having two relatively flat members each having a portion arranged in overlapping relation with the similar portion of the other plate member and held in extended position within the bank opening by the fastening means.

Moreover, my invention is of such a nature that when the fastening means is loosened, the plate members may be moved toward each other thus shortening the closure plate for removal from the opening in the bank.

A further object is to provide a simple and inexpensive closure plate easily adapted for use on present day or antique banks; the several parts of such device always remain attached to one another.

The above objects and advantages have been accomplished by the device shown in the accompanying drawings, of which:

Fig. 1 is a perspective view of a typical coin bank, with portions thereof broken away to show my invention as used in connection therewith;

Fig. 2 is an enlarged fragmentary sectional view taken on line II—II of Fig. 1;

Fig. 3 is a plan view of a slightly modified form of my invention;

Fig. 4 is a fragmentary sectional view taken on line IV—IV of Fig. 3;

Fig. 5 is a plan view of a closure plate of another modified form;

Fig. 6 is a side elevation of the form of invention shown in Fig. 5;

Fig. 7 is a view similar to Fig. 6 but shows the plate in its contracted position and partially removed from the opening; and,

Fig. 8 is a perspective view of still another modification of my invention.

As illustrated in Fig. 1, the bank comprises a bottom member 10 which supports the side walls

2

11 and top 12 of the bank. The bottom member is provided with an access opening 13 through which the coins deposited in the bank may be removed when desired. My plate 14 comprises two plate members 15 and 16 having their inner ends united by a rabbet joint 20 formed by the overlapping portions 21 each of which is preferably substantially one-half the thickness of the plate member. The plate members when joined by the rabbet joint are so proportioned that they substantially fill the opening 13 in the bottom member of the bank. The plate members are preferably of substantially the same thickness as the bottom member 10, and each of them is provided with an offset flange member 22 which is designed to engage the inner face or top surface of the bottom member when the plate is within the opening and in its extended position, thereby bringing the surfaces of the plate substantially flush with the surfaces of the bottom member. In this type of bank, the plate 14 is held in place preferably flush with the inside surface of the bottom 10 by means of ridges 17 extending upwardly from the bottom and over the adjacent edges of the opening, as clearly shown in Fig. 1. The two members of the plate are held in fixed extended positions by means of a fastening screw 23, which passes through the overlapping portions 21 of the members. Since the screw must be accessible from the outside of the bank, it is threaded into the member 16 and a countersunk hole is provided in the member 15 for the flat head of the screw. The fastening screw in all forms of my invention is sufficiently long to permit ample separation of the plate members to accomplish the desired results. It is preferable to have the hole which is engaged by the screw slightly larger in diameter than the body of the screw so that it will be loosely engaged by the screw when the latter is partially unscrewed. As clearly shown by the dot-and-dash lines in Fig. 2, the two plate members may be positioned at an angle to each other following the loosening of the screw, which will permit the plate to be contracted sufficiently so that one of the flanges 22 may be moved past the edge of the opening, thereby permitting the plate to be removed from the opening.

The size and position of the flanges 22 of my plate will vary according to the design of the bank bottom to which my invention is to be adapted. For instance, the bank shown in Fig. 3 has certain ridges 25 and 26 which are arranged adjacent the opening and which extend upwardly from the bottom 30. The flange 27, therefore, of the plate member 31 may be nearly the full width of the opening 32 in the bottom, whereas the flange 33 of the plate member 34 is relatively narrow. Furthermore, in this type of bank, detent tabs 35 are provided on opposite sides of the opening 32. As shown in Fig. 4, these tabs are offset and have their under surfaces sub-

stantially flush with the top surface of the bottom wall, thereby acting as detents to limit movement of the plate inwardly within the opening. The fastening means of this form of the invention is provided by the screw 37.

In certain types of banks where the access opening is not provided with retaining or detent ridges or tabs, it is necessary to provide means to retain the plate within the opening of the bottom. This is accomplished by the form of invention shown in Figs. 5 to 7. As here shown, the plate 40 is composed of plate members 41 and 42 united by means of a rabbet joint 43 formed by overlapping portions 44 of each member. The fastening means 45 is screwthreaded into the member 41 and passes through a suitable aperture formed in the member 42. In this form of invention, a slot 46 is extended from the screw opening toward the outer end of the member, whereby the relative movement of the two parts may be facilitated when the plate is to be removed from the opening. For reasons just above pointed out, each of the plate members 41 and 42 is provided with two spaced lower retaining tabs 50 and with a centrally arranged upper retaining tab 51. As clearly shown in Figs. 6 and 7, the tabs 50 and 51 are arranged in offset relation with the body of the plate 40 and engage respectively the bottom and top surfaces of the bottom 52 of the bank, shown in dot-and-dash lines. When the plate of this form of invention is to be contracted and removed from the opening, it is only necessary to loosen the fastening screw sufficiently to permit the overlapping portions 44 to ride over the adjacent outer surfaces of the respective members whereupon the members may be moved relatively to each other, as shown in Fig. 7 to permit the plate to be sufficiently contracted to be removed from the opening 53 in the bottom 52 of the bank.

In the form of invention shown in Fig. 8, the plate 54 is formed with a plate member 55 having a locking tab 56 spaced some distance from the free edge of the member for engagement with the inner surface of the bottom wall of the bank while the projecting portion of the member 55 engages the bottom surface of the bottom of the bank. Spaced retaining tabs 60 are formed along the free end edge of the plate member 61 for engagement with the upper surface of the bottom of the bank when the plate is engaged with the opening and is in extended position not shown. The screw 62 which passes through the rabbet joint 63 serves to draw and hold the members together.

From the foregoing, it will be clear that when the closure plate of either form is to be removed from the opening of the bank, it is only necessary to release and unscrew the fastening means part way. This will allow the two members of the plate to assume the angular position shown in Fig. 2 or the overlapping position shown in Fig. 7. In either of these positions, the plate will be contracted sufficiently to permit its being readily removed from engagement with the opening of the bank. In moving the plate members to the angular positions, the outer edge of one of the overlapping portions may be rested in and hinged about the shoulder formed by the overlapping portion of the other member. If this does not permit sufficient contraction to remove the plate from the opening, the engaged edge of the overlapping portion may be moved to thereby permit additional contraction of the plate.

While I show and describe closure plates of rectangular shape, it is obvious that my invention is applicable to plates of other shapes, such as circular.

5 What I claim is:

1. A closure plate for disposition within the opening of a wall, comprising two separate plate members having their inner adjacent ends of reduced thickness and in overlapped relation with each other, detent means carried by said plate members for retaining said members when assembled within the opening of the wall, a centrally arranged fastening screw for securing said plates together, said screw passing through said ends and having its axis perpendicular to the face surfaces of the plate members, said screw being threaded into the inner end of one of the plate members and loosely engaging the other plate member, said fastening means when loosened permitting contraction of said plate for placement within the opening of the wall.

11 2. A closure plate for disposition within the opening of a wall, comprising two separate plate members having their inner adjacent ends of reduced thickness and in overlapped relation with each other, detent means carried by said plate members for retaining said members when assembled within the opening of the wall, a centrally arranged fastening screw for securing said plates together, said screw passing through said ends and having its axis perpendicular to the face surfaces of the plate members, said screw being threaded into the inner end of one of the plate members and passing through an enlarged aperture formed in the end of the other plate member, said fastening means when loosened permitting relative endwise movement of said plate members, whereby said plate will be contracted for placement within the opening of the wall.

16 3. A closure plate for disposition within the opening of a wall, comprising two separate plate members having their inner adjacent ends of reduced thickness and in overlapped relation with each other, detent means carried by said plate members and by said wall for retaining said members when assembled within the opening of the wall, a centrally arranged fastening screw for securing said plates together, said screw passing through said ends and having its axis perpendicular to the face surfaces of the plate members, said screw being threaded into the inner end of one of the plate members and passing through an enlarged aperture formed in the end of the other plate member, said fastening means when loosened permitting relative endwise movement of said plate members, whereby said plate will be contracted for placement within the opening of the wall.
